STITCHLESS BILLFOLD WITH INTER-LOCKED POCKET FORMING FLAPS

Emil Karl Renz, Dedham, Mass., assignor, by
mesne assignments, to Debonair, Inc., Boston,
Mass., a corporation of Massachusetts

Application February 27, 1945, Serial No. 579,957

4 Claims. (Cl. 150—38)

1

The present invention relates to a wallet or bill fold and more particularly to the type which provides a long pocket lengthwise of the wallet for holding bills and several other smaller pockets formed in each half of the bill fold which face one another when the bill fold is folded about a central section.

One of the difficulties encountered in making a bill fold with a number of pockets and compartments is that when folded the wallet has not enough flexibility to accommodate the bills and cards in the various pockets without causing clumsy bulges or distortion of the wallet. This causes the wallet to wear badly and as a result it becomes creased and has a generally poor appearance.

In my prior patent issued January 9, 1945, No. 2,366,875, I provided a special stay member which was self-adjustable in the bill fold when the wallet was folded. The present invention goes further than this in providing a self-adjustable combination stay and divider thus permitting self-adjustment of all the inner longitudinally running members within the outer wall or cover of the wallet itself. This construction permits the wallet to be folded on the center and yet allows both the divider and the stay member to take up positions so that no wrinkles or bulges will occur. The divider is the sheet running lengthwise of the long pocket and provides a means for separating bills of various denominations, if desired, while the stay member together with overlapping flaps form the inner wall of the wallet, these flaps in the present invention being formed as extensions of the outer wall.

In the present invention the divider and stay member are linked together and are adjustably interlocked with flap elements formed as extensions of the outer wall or face of the wallet or bill fold. Other features and advantages in the present construction will more fully appear from the description in the specification below when taken in connection with the drawings illustrating an embodiment of the invention in which:

Figure 1 shows the wallet in an open position looking at the inner face.

Figure 2 is a plan view of the combined stay member and divider with the stay member shown in the front.

Figure 3 shows a view with portions broken away showing an outer cover member with some of its flaps unfolded in combination with the member indicated in Figure 2.

Figure 4 shows a section substantially on the line 4—4 of Figure 1, and

2

Figure 5 shows a section substantially on the line 5—5 of Figure 1.

As indicated in Figure 1, 1 is the outer face cover or outer wall of the wallet, 2 is the divider in the long pocket and 3 is the inner stay member. A longitudinal pocket 4 extending the whole length of the wallet is formed between the wall 1 and the stay member 3 and is divided into two sections by the divider 2. The stay member 3 has facing it, both on its inner face and its outer face, portions of end flaps 5 and 6 which are extensions from the ends of the outer wall 1. As viewed in Figure 1, the portions 7 and 8 of the end flaps 5 and 6 respectively are the outer facings or the facing covers of the wallet. These flaps together with flaps 9 and 10 also extending from the outer cover of the wallet at its lower long edge form respectively two transverse pockets 11 and 12. Facing sheets 13 and 14 cemented around 10 their periphery at the rear of the flap portions 7 and 8 form the back walls of the pockets 11 and 12. Another set of pockets 15 and 16 with openings substantially parallel to the center line of the wallet on either side thereof are formed with 15 the back wall comprised of the stay member 3 and the front wall comprised of the flap portions 7 and 8. Flap extensions joined to the sections 16 7 and 8 fold over on the back of the stay member 3 when viewed from the position of Figure 1. 20 These flap extensions are shown in Figure 3 at 17 and 18.

It should also be noted that these flap extensions 17 and 18 are positioned between the stay element 3 and the divider member 2 with which 25 units they interlock, as will be presently explained.

The construction of the stay and divider is shown more particularly in Figure 2. The divider 2 extends almost to the ends of the long pocket 40 in the wallet. At the end edges extending T-shaped tabs 19 and 20 are formed with the stem of the tabs joined to the end edges of the divider element and the cross portion of the T arranged at right angles to the long dimension of the divider. Each of these T-shaped tabs 19 and 20 pass over the rear face of the stay member 3 and through slots 21 and 22 respectively in the stay member 3, thus bringing the cross portions of the T, 23 and 24, respectively in between the stay member and the divider. The cross portions of the T hold the stay member and divider in an interlocked position at both ends with each other yet permit longitudinal adjustment of the stay member and divider with respect to each other.

In the assembly of the wallet, the end flaps 7 and 8 joined to the outer wall 1 at its ends are folded over to cover the end portions of the outer face of the stay member, it being assumed that the stay member and divider are in the position shown in Figure 3 in which they lie against the outer wall 1. The flaps 17 and 18 are then tucked in between the stay member and divider, the rectangular cut-out portions 25 and 26 fitting about the stems 20 and 19 respectively of the divider. The slots or rectangular recesses 25 and 26 provide sufficient freedom for the stems 19 and 20 so that the stay member and divider may be adjusted together in position and with respect to one another by the folding of the bill fold or the placing of bills in it. Tabs 21 and 28 at the ends of the flaps 17 and 18 in the folded positions of the end flaps are folded over the outer surfaces of the flaps 7 and 8 to which they may be cemented in place.

Since the flaps 7 and 8 with their extending portions 17 and 18 all form a part of the outer wall or face 1 of the wallet, and further, since these end flaps are joined to form a sheath about the divider 3, there is no need of stitching the end edges of the wallet to stitch the flap 18 into place.

As has been previously stated, in connection with the description in Figure 1, two pockets are formed, one in each inner face of the wallet as indicated by 11 and 12. The back walls of these pockets are formed by the members 13 and 14 respectively while the front walls are completed by the members 7 and 8 in which the three-sided slots 29 and 30 are disposed which are engaged by the flaps 9 and 10, previously mentioned, extending from the lower edges of the outer wall 1. These outer finishing flaps are folded over with the folded edges 31 and 32 coming in contact with the diagonal edges of the slots 29 and 30 and with the side edges of the flaps 9 and 10 fitting behind the walls 7 and 8 in the side edges of the slots. For this purpose the finishing flaps 9 and 10 are cut inwardly at 33, 34 and 35, 36 respectively, thus permitting the sides of the flaps 9 and 10 to be fitted behind the walls 7 and 8.

It should be noted that finishing margins are provided, one of which, 37, positioned in the central portion of the wallet at the lower end, is faced against the inside of the outer wall and the other, 38, at the upper edge of the outer wall which is also faced on the inner side of this wall.

In connection with Figure 2, it should be noted that a wide extending tab 39 attached to the lower end of the stay member 3 is bent over behind itself and cemented to it.

A further extending tab 40 is provided at the top of the stay member 3 so as to provide a finished surface in the central section of the stay member between the pockets 15 and 16.

Having now described my invention, I claim:

1. A wallet of the type described formed of an outer wall having end flaps and a combination divider and stay member having a joining strip joining the divider and stay member at their sub-ends, the combination member extending substantially the length of the wallet and parallel to the outer wall, a portion of the end flaps lying in between the stay and divider and another portion lying externally of the stay member, the

portion of the end flap lying between the stay and divider having means at the end side of the flap adjustably interlocking with the joining strip of the stay and divider providing longitudinal play to permit longitudinal adjustment of the stay and divider with respect to the outer wall.

2. In a wallet of the type described, an outer wall having an end flap with a side extension thereof, a divider and stay member, means joining said members together at their ends in a section substantially narrower than either member, said end flap being adapted to be folded over the exposed face of the stay member with the side extension lying between the stay member and the divider, said side extension being recessed at a place along its end edge to provide an interlocking engagement with the joining section between the stay and divider, said recesses providing sufficient freedom for the joining section to permit longitudinal adjustment of the stay and divider in the wallet.

3. A wallet of the type described formed of an outer wall having end flaps and a combination divider and stay member joined at their ends in a member narrower in width than either the stay member or the divider, said stay member and divider extending substantially the length of the wallet with faces parallel to the outer wall, said end flaps having side extensions and being folded over the exposed face of the stay member with the said extensions lying in between the stay member and divider and having a cut-out section engaging the joining section of the stay and divider at their ends providing interlocking means between said extensions and the divider and stay member and permitting adjustment of the latter longitudinally of the wallet, said side extension members having extending tabs adapted to fold over the face of the end flaps forming a sheath in which the stay member is positioned.

4. In a wallet of the type described formed with an outer wall having end flaps and a combination divider and stay member, means adjustably joining said divider and stay member at their ends comprising a T-shaped tab with the stems extending from the ends of one of the members and engaging in transverse slots in the other member, said end flaps having side extensions and being folded over the face of the stay member with the side extensions lying between the stay member and divider and having a recessed edge enclosing the stem of the T members and permitting longitudinal adjustment of the stay member and divider combination with respect to the wallet.
